United States Patent Office

Des. 210,250

Patented Feb. 20, 1968

210,250

COMBINED BOTTLE AND CAP THEREFOR

James L. Linn, Jr., Maumee, Ohio, assignor to Owens-Illinois, Inc., Toledo, Ohio, a corporation of Ohio

Filed Mar. 29, 1967, Ser. No. 6,433

Term of patent 14 years

(Cl. D58—6)

FIG. 2

The sides not shown are mirror images of the sides shown.

I claim:

The ornamental design for a combined bottle and cap therefor, substantially as shown and described.
